United States Patent Office.

JAMES G. CLARKE, OF CINCINNATI, OHIO.

Design No. 3,453, dated April 27, 1869.

DESIGN FOR A COOK'S STOVE.

The Schedule referred to in these Letters Patent and making part of the same

To all whom it may concern:

Be it known that I, JAMES G. CLARKE, of Cincinnati, Hamilton county, State of Ohio, have invented or produced a new and original Design for a Cooking-Stove; and I do hereby declare the accompanying drawings, which are made a part of this specification, to form a full, clear, and exact delineation of the same.

The accompanying drawing is a perspective view of the stove.

I claim as new, and of my invention—
The ornamental design of cooking-stove, substantially as herein exhibited.

In testimony of which invention, I hereunto set my hand.

JAMES G. CLARKE.
